UNITED STATES PATENT OFFICE.

HERBERT A. AUSTIN, OF BOSTON, MASSACHUSETTS.

DESIGN FOR A DISPLAY AND DISPENSING CABINET.

41,371.

Specification for Design.

Patented May 9, 1911.

Application filed February 24, 1911. Serial No. 610,625. Term of patent 7 years.

To all whom it may concern:

Be it known that I, HERBERT A. AUSTIN, a citizen of the United States, residing in the county of Suffolk, city of Boston, and Commonwealth of Massachusetts, have invented a new, original, and ornamental Design for Display and Dispensing Cabinets, of which the following is a specification, reference being had to the accompanying drawing, which forms part of this application, and in which—

Figure 1 is a front perspective view of the cabinet; and Fig. 2 is a rear perspective view of the cabinet showing the storage drawers.

I claim:

The ornamental design for a display and dispensing cabinet, as shown.

HERBERT A. AUSTIN.
